UNITED STATES PATENT OFFICE

103,771

DESIGN FOR BATHING TRUNKS

Theodore R. Upland, Burlingame, Calif., assignor to Gantner & Mattern Company, San Francisco, Calif., a corporation of California

Application January 15, 1934, Serial No. 50,407

Term of patent 14 years

To all whom it may concern:

Be it known that I, Theodore R. Upland, a citizen of the United States, residing at Burlingame, county of San Mateo, and State of California, have invented a new, original, and ornamental Design for Bathing Trunks, of which the following is a specification, reference being had to the accompanying drawing, forming a part thereof.

In the drawing Fig. 1 is a front view of the trunks with the belt thereon.

Fig. 2 is a rear view of the trunks with the belt thereon.

The shading on the body of the trunks represents color in contrast with the color of the belt.

I claim:

The ornamental design for bathing trunks as shown and described.

THEODORE R. UPLAND.
